UNITED STATES PATENT OFFICE.

RICHARD F. HOYT, OF PHILADELPHIA, PENNSYLVANIA, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,298,720.

Specification of Letters Patent.

Patented Apr. 1, 1919.

Application filed January 19, 1915. Serial No. 3,031.

To all whom it may concern:

Be it known that I, RICHARD F. HOYT, a citizen of the United States, residing in Olney, Philadelphia, in the county of Philadelphia and State of Pennsylvania, have invented certain new and useful Improvements in Combined Type-Writing and Computing Machines, of which the following is a specification.

10 This invention relates to typewriting machines or combined typewriting and computing machines, and more particularly to mechanism for effecting the return of the carriage and operation of the general operator of the computing mechanism. In combined typewriting and computing machines of the Underwood-Hanson type, in connection with which the present invention is illustrated, the numeral keys operate through 15 suitable mechanism to set up pins connected to rack bars, which, when a number has been written, are actuated by a general operator, to run up the numbers on the computing wheels. The general operator may 20 be driven by an electric motor connected thereto through suitable transmission gearing comprising clutch members adapted to be connected by a clutch shifter which also operates to establish a circuit for the motor 25 so that the general operator is driven through one cycle, the clutch members being then automatically disengaged to disconnect the general operator from the motor.

In the machine shown in patent to Hart, 5 No. 1,238,908, dated September 4, 1917, to which the present invention is hereinafter shown as applied, the motor is used for returning the carriage, and for this purpose, is connected through suitable gearing also 10 comprising a clutch to drive the carriage. Means is therein provided for automatically actuating the clutch shifter to connect the motor with the general operator and to close the motor circuit as the carriage completes its forward travel; means also being provided for actuating the clutch between the carriage and the motor when the motor starts, so that the carriage is returned by the motor, and the general operator actuated 15 concomitantly. A manual key is therein shown as provided to close the switch for the motor and operate the clutch between the motor and carriage for returning the latter from any intermediate position.

The electric motor of that machine is connected through suitable gearing, including a clutch, to a pinion running in mesh with a rack on the carriage for driving the latter. During the forward travel of the carriage, the motor may remain at rest, and as the carriage completes its forward run, may operate through suitable connections to establish a motor circuit, and thereby start the motor. Right and left hand adjustable margin stops determine the limits of travel of the carriage, and also have connected thereto, cams operated by an arm on the carriage to effect the opening and closing of said clutch at the beginning and completion of the return travel of the carriage. The left-hand margin stop is adjustable along a rack bar, which may be swung downwardly by an arm on the carriage striking a cam connected to the stop, and thereby swing forwardly a depending arm connected to said rack. The depending arm controls a latch to effect the operation of the clutch. The latch is vibrated by means of a cam rotated by the motor, so that when the latch is moved to said operative position, its vibratory movement is transmitted to a clutch shifting lever to connect the clutch members, and thereby connects the carriage to the motor. The clutch is therefore operated by power supplied directly by the motor. Connected to the right-hand margin stop for adjustment therewith, is a cam operated by the carriage at the completion of the return movement, and operable through suitable connections to release the clutch.

In the machine referred to, the switch for closing the motor circuit as the carriage is completing its forward movement, is connected with a clutch shifter, which, when the switch is moved to circuit-closing position, effects a clutch connection between a worm wheel driven by the motor, and a shaft, which, when rotated, drives the general operator of the computing mechanism through one cycle of operation, the clutch being then automatically released and the switch opened. To close the motor circuit independently of the switch, and thus permit the return of the carriage to be completed after the connection from the motor to the general operator has been broken, a second switch is automatically operated to close another circuit through the motor. A

separate switch, which is utilized to maintain the motor circuit closed during the return of the carriage, is automatically operated concomitantly with the operation of 5 the clutch which connects the motor to return the carriage.

A manual key for returning the carriage from any intermediate position may be connected to operate a switch to close the motor 10 circuit, and may also actuate the latch for effecting the operation of the clutch between the motor and the carriage. The switch operated by the manual key may be the same as the above-mentioned automatically operated switch which maintains the motor circuit closed during the return of the carriage.

One of the objects of the present invention is to provide means by which the action of the motor, in returning the carriage, may 20 be suspended or delayed after the carriage, on its forward travel, has reached the point where these operations normally take place. It is often desirable, when the carriage reaches this point, to print a star to indicate 25 a clear condition of the adding mechanism or write a word, or to make some other writing. This cannot be done if, on reaching that point, the motor immediately starts the carriage return. The means provided in the 30 present invention for accomplishing this delay or suspension of the motor action consists in a margin button or its equivalent, which may be set at will to render inoperative the motor connections. In its preferred 35 form, this feature of the invention consists of a push button which may be held, against the action of a spring, in a position where it holds inoperative a setting device for the motor connections, the setting device having 40 been previously released by the carriage at the end of the latter's normal forward travel, and being thus ready to perform its usual function as soon as the push button is released after the additional writing has been 45 made.

Another object of the invention is to provide a device which sets the connection from the motor to the carriage, with a spring or other actuator so that it may operate independently of power derived from the carriage or from the latter's spring motor, and may be positively held in effective position during the entire return movement of the carriage. To this end, in its preferred form, 50 the setting device is spring-actuated, and is only tripped by the carriage, instead of being positively actuated thereby, as in the machine of the application referred to.

A further feature of the invention is to 60 have the circuit-closing device for the motor circuit, which maintains the carriage drive after the computing operation is completed, also operated in the same general manner as the connection-setting device just described, 65 so that that circuit is maintained independ-

ently of the carriage and its spring motor; and in this invention, the same device is preferably employed to set the motor driving connection, and to establish and maintain the auxiliary motor circuit.

Another object of the invention is to have the connection from the manually operated carriage-return key, (which forms part of the machine of the application referred to), of such nature that continued pressure on that key during the carriage return is unnecessary; and of such nature that no force, other than a light touch, need be applied to that key in establishing the driving connections. In its preferred form, this feature of the invention comprises a spring-operated device which is tripped and released by the key, and which, when so tripped, is thrown by its spring to establish the motor driving connections, and to close the circuit through the motor.

It is a feature of the invention that one and the same device for establishing the carriage-return drive from the motor, and for closing a circuit through the motor, may be, and preferably is, operable, not only by the carriage at the end of the latter's normal forward travel but also by the manual key to return the carriage from any intermediate point, and is also the device, the action of which may be suspended by the margin button.

Other features and advantages will hereinafter appear.

In the accompanying drawings,

Fig. 1 is a part sectional side elevation of the machine.

Fig. 2 is a view in front perspective showing certain of the carriage-controlled motor connections, and related parts in normal position.

Fig. 3 is a view in front perspective showing certain of the parts shown in Fig. 2, when the operation of the same is being suspended by the margin button.

Fig. 4 is a view in side elevation of the parts shown in Figs. 2 and 3, together with the carriage and certain other parts, in the position assumed during the return drive of the carriage.

Fig. 5 is a detail view of the switch members associated with the transmission mechanism.

Fig. 6 is a view similar to Fig. 2 except that certain parts are omitted to more clearly show the restoring connections.

Fig. 7 is a detail view of the margin button device for suspending the action of the motor connections.

Fig. 8 is a diagrammatic view of the switch and motor circuits.

Fig. 9 is a cross sectional view of the junction box for the electric conductors.

The alphabet keys 1 and the numeral keys 2 are connected to key levers 3 and 4, ful-

crummed at 5 and connected through bell cranks 6, to the type-bars 7, on a fulcrum rod 8. When a key is depressed, the corresponding type-bar is swung upwardly and 5 rearwardly about its fulcrum to bring the types 9 against the printing face of the platen 10. The platen frame 11 is shiftable as usual to upper and lower case positions, and is mounted on a carriage 12 which trav- 10 els on front and rear guide rails 13 and 14 respectively. The roll 15 on the platen frame runs on a rail 16, shiftable up and down by the usual mechanism to move the platen between upper and lower case posi- 15 tions. The carriage may be driven in a letter-feed direction by the usual spring-motor, (not shown) connected through a draw- 20 band to the carriage. The letter-feed movement of the carriage may be controlled by the usual letter-feed mechanism, (see Fig. 1) comprising escapement dogs 18, coöperating with an escapement wheel 19, these dogs being actuated by a universal bar 20, operated by heels 20^a on the type-bars. The operation 25 of the type-bars permits a step-by-step rotation of a pinion 21, connected to the escapement wheel 19, and running in mesh with the carriage rack 22, whereby a letter-feed travel of the carriage is effected. 30 The tabulator mechanism may comprise keys 23 on levers 24 fulcrumed at 25, and at their rear ends extending beneath vertical plunger stops 26, which, when the keys 23 are depressed, are projected upwardly into 35 the path of column stops on a rack bar 27 on the carriage.

An electric motor M is provided for automatically returning the carriage, and for 40 operating the general operator of the computing mechanism. The gearing for driving the carriage from the motor comprises a pulley fixed to the motor shaft 29, and connected through a belt 30 to a sheave 31 on a shaft 32, to which shaft is also secured a 45 sheave 33 connected through a belt 34 to a sheave 35 on a clutch shaft 36. Fixed to the shaft 36 is a member 37 of a clutch, which also comprises a member 38 loose on shaft 36, and shiftable into and out of engagement 50 with the member 37. Fixed to the shiftable member 38 is a pinion 39, in mesh with a rack 40 on the carriage, for returning the carriage and operating the line-spacing mechanism. The clutch is operated to connect 55 the motor M to return the carriage when the latter completes its letter-feed movement, at the end of each line, the operation of the clutch being controlled by a left-hand margin stop 41, and by a right- 60 hand margin stop 41^a (see Fig. 2).

The margin stop 41 is slidably mounted on a rod 42, and held in any desired position of adjustment by a rack 43 coöperating with a pivoted dog on the stop, actuated by a fin- 65 ger lever 44. The rack bar 43 is pivoted by

means of arms 54 at the ends of the rack bar, to rock on the shaft 42 as a pivot. The rack bar 43 is held up in its normal position by a coil spring 46 (see Fig. 2). As the carriage approaches the limit of its forward movement, determined by the position of the stop 41, a roller 47 on the carriage, engages a cam 48, and depresses the rack bar sufficiently to operate a signal bell through the usual mechanism (not shown). When the carriage has about completed its forward movement, the roller 47 strikes a cam surface 50 on an arm 51, pivoted at 52 to a member forming an extension of the margin stop and having a lug 53 bearing on the rack bar 43, thereby further depressing the rack bar 43.

This movement of the rack bar causes depression of a link 54, pivotally connected to and depending from the rack bar, and pivotally connected at its lower end to one end of a lever 55, fulcrumed at 56 on the machine frame. The other end of the lever 55 lies under a pin 57 on a rod 58, so that when the link 54 is depressed, and the lever 55 thereby rocked, the latter, by engagement with the pin 57, causes the rod 58 to be slightly lifted. The lever 55 is preferably rounded at 59 where it engages the pin 57, so that the thrust on the pin 57 may always be an upward thrust, and so that no resistance may be offered by the lever 55 to free longitudinal movement of the rod 58 while the pin 57 is thus engaged. The rod 58 is pivoted at one end, at 60, to an arm 61 fast to a rock shaft 62. The other end, 63, of the rod 58 is free. A coil spring 64, attached to the machine frame and to the rod 58, acts to throw the rod 58 rearwardly when a shoulder 65 on the rod 58 is lifted out of engagement with a fixed holding member 66. A cut 68 in the holding member provides for engagement of the latter with the shoulder 65 of the rod 58, and also limits the upward throw of the rod 58.

Until the carriage is to be returned, the rod 58 is held in the Fig. 2 position by the shoulder 65. When, however, the arm 54, acting through lever 55, swings the rod 58 upwardly around its pivot 60, the shoulder 65 is released, and the spring 64 throws the rod 58 rearwardly. The rod 58, moving rearwardly under the action of spring 64, carries with it the arm 61 on shaft 62, and thereby rocks that shaft. Attached to the shaft 62, near its other end, is another arm 69, connected by a link 70 to one end of a lever 71, which acts as a latch to control the operation of the clutch 37. 38 for connecting the carriage to the motor M, so that the carriage may be returned by the motor when the roller 47 on the carriage reaches the stop 41.

As the carriage completes its forward movement, the circuit for the electric motor 130

M is closed by means hereinafter described, so that the motor is running, and the clutch member 37 therefore rotating at the time the roller 47 actuates the link 54. The rear face 5 of the clutch member 37 is formed with a cam 72, against which bears the upper end of a bell crank lever 73, fulcrumed on a rod 74, and having an arm 75 extending forwardly from the shaft 74. An arm 76 on the rod 10 74 is connected by a spring 77 to the arm 75, the movement of the arms 75 and 76 toward each other being limited by a stop 78 on the arm 75. The bell crank lever 73, therefore, is vibrated by the rotating cam 72, 15 being held against the cam by a spring 79; and it imparts a vertical reciprocating motion to the latch lever 71, which is pivoted to the arm 76. The upper end of latch 71 is thus vibrated in front of a horizontal arm of 20 a bell crank lever 80 fast on a rock shaft 81 which is supported on a stationary bracket 82; the latch 71 being in position to clear bell crank arm 80 at the time the motor is started. When, however, the carriage, at the 25 completion of its forward run, operates the cam 50 on the left-hand margin stop, as above described, to release the bar 58 to its rearward movement with rock shaft 62, the link 70, actuated by arm 69, forces the upper 30 end of the latch against the end of the bell crank 80; and, as the latch is carried downwardly by the arm 76 which is now vibrating, it engages beneath the bell crank 80; so that, when the arm 76 again rises, the bell 35 crank 80 is swung about its pivot 81, and a knob 83, on the upper end of the bell crank 80, and which runs in an annular groove 84 in the hub of the pinion 39, carries said pinion rearwardly to connect the clutch members 37, 38. The pinion 39, thus connected to 40 the motor, drives the rack bar 40 to return the carriage. The line-space mechanism may also be operated automatically when the carriage is returned by any approved 45 mechanism as, for example, that disclosed in the patent to Edward F. Kunath, No. 836,932, dated November 27, 1906.

Means hereinbefore referred to and shown in said Patent No. 1,238,908, for establishing the motor circuit prior to the return of the carriage, when a line has been completed, will now be described. A stop 85, (see Fig. 1) on the rack bar 27, is provided with a tappet 86 into the path of which projects a 5 cam lug 87 on a lever 88 pivoted intermediate its ends to the framework 179 of the typewriting machine; the stop 85 and tappet being adjustable along the rack 27, and preferably positioned to engage the lug 87 shortly before, or just as the carriage completes its forward travel. The lever 88 operates through a pull link 89 to rotate a bell crank 90, to which is attached a bar 91, the 10 end of which overlies the rear end of a lever 92. When the bell crank 90 is rocked

by link 89, it releases lever 92 to the action of a spring 93 which swings it about its fulcrum 94, causing it by means of a pin 95, to depress a rod 96 on which the pin is mounted. Rod 96 rocks a lever 97, thereby 15 lifting a stop pin 98, which is also in engagement with lever 97. This stop pin releases a clutch-operating ring 99, which operates to establish an electric circuit for the motor, and also operates a clutch to connect 20 the motor to the mechanism for driving the general operator of the computing mechanism.

The clutch-controlling ring 99, when released as just described, is rotated by a 25 spring 100 in the direction of the arrow, (Fig. 1) to carry a roller 101 upwardly and jam it between the cam surface of an annular flange 102, formed on a disk fixed to a shaft 103, and the hub of a worm gear 104, 30 loose on said shaft. The worm gear 104 is thus connected to the shaft 103, and itself is driven by the worm 105 on the motor shaft 29. The ring 99 carries contact lugs 99^a, (see Fig. 5) on a metal disk connected to, but 35 insulated from the member 99, which, when the ring is rotated by the spring 100, engage spring contact arms 150 and 151, thereby 40 electrically connecting the latter, and establishing a circuit through the motor M. 45 The motor is thereby started, and operates through the mechanism heretofore described to return the carriage.

The motor also operates through the worm gearing 104, 105, to rotate the shaft 103, to 50 which is connected a crank, (not shown) to reciprocate a slide 106, connected to the general operator 107 of the computing mechanism. This slide is given one complete reciprocation, and actuates the general operator through one complete cycle by the time the worm gear 104 has made one complete rotation, and is again released from the motor by the stop pin 98, which in the meantime has been returned into the path of the 55 lug 108 on the clutch operator 99. This return of pin 98 is effected as soon as the carriage on its return movement releases the link 89 and permits a spring (not shown) to return arm 91 to normal position, the latter in turn returning lever 92 to normal position 60 against the action of spring 93, and permitting a spring (not shown) to swing lever 97, together with pin 98, to normal position.

In order to maintain the motor circuit independently of the switch, hereinbefore described as operated by contacts carried by the clutch ring 99, the following means is provided. The arm 61 (see Fig. 2) on the rock shaft 62, is pivoted at its end to a 65 slide bar 110 which is supported at its free end on the machine frame 179. The bar 110 at 111, has a pin-and-slot engagement with a bell crank lever 112, pivoted at 113 to the frame. One arm of the bell crank 112 en- 70

gages a piece of insulation 114 on a switch arm 115 pivoted at 116, to, and in electrical connection with a contact member 117 which is in electrical connection with one terminal 5 of the motor M. The switch 115 has a lug or contact 118 adapted, upon depression of the switch, to engage another contact 119, in electrical connection with the other terminal of the motor M. A coil spring 120 holds 10 the switch 115 normally out of reach of the contact 119. When, however, the carriage has moved to the point where the rod 58 is thrown rearwardly to operate the clutch 37, 38, this movement of the rod 58 causes 15 the bar 110 also to be moved in the same direction, and the bell crank 112 thereby to be rocked to depress the switch 115, from the Fig. 2 to the Fig. 6 position, thus establishing a motor circuit independent of that established by the clutch ring 99 to effect the 20 drive of the general operator from the motor. The circuit established by the switch 115 remains closed after the general operator clutch 99 has, by returning to normal position 25 on completion of the general operator cycle, broken the circuit which it established.

As the carriage has about completed its return movement, the clutch 37, 38 is opened 30 by the following mechanism to disconnect the carriage from the motor. Referring to Figs. 2 and 6, the right-hand margin stop 41^a is mounted on the shaft 42 for adjustment longitudinally of the carriage, and is 35 held in adjusted position by a rack 125, with which engages a pawl (not shown) pivoted to the margin stop and operated by a finger piece 126. Connected to the margin stop for adjustment therewith, is an arm 127 splined 40 on the rock shaft 42, and carrying a cam 128 in the path of the roller 47 on the carriage. The arm 127 may be connected to the stop 41^a by means of a lip 129 on the stop entering a notch in the arm, such connection permitting 45 the arm to rock with the shaft 42. As the carriage nears the end of its return movement, the roller 47 strikes the cam 128 and rocks the arm 127, and with it the shaft 42, thereby swinging forwardly a depending 50 arm 130 fixed to the shaft 42. This movement of the arm 130 effects a forward movement of a link 131, which connects the end of arm 130 to the end of an arm 132 fast to the shaft 81, which, when rocked by the arm 55 132, causes the bell crank 80 to separate the clutch members 37, 38, thus breaking the driving connections of the carriage from the motor.

When the shaft 42 is rocked by the roller 60 47, upon return of the carriage, it effects the movement of the bell crank 80 to separate the clutch members 37, 38, but the latch 71 has not been removed from under the end of the bell crank 80. It will be remembered that the latch 71 is drawn under

the bell crank 80 by the shaft 62, acting under the impulse of the spring 64 on the bar 58, and continues to be held in that position by the spring 64 during the return movement of the carriage. In order that the 70 latch 71 may be withdrawn from under the bell crank to permit the clutch members 37, 38 to be separated, and also to the end that the shaft 62 may be rocked to break the motor circuit established through the contacts 118 and 119, and to return the bar 58 to normal position against the action of the spring 64, the following means is provided. Fast to shaft 42 is an arm 133 connected by 75 a link 134 to a two-armed lever 135, pivoted at 136 to the machine frame. One end of the lever 135 connects with link 134, while the other end of said lever connects to link 137, in turn connected to an arm 138, fast to the rock shaft 62. The arm 133 acts at the same 80 time the arm 130 acts when the shaft 42 is rocked, but is of such length, and the connections from it and the shaft 62 are such as to cause the shaft 62 to move the latch 71 out of the path of the clutch bell crank 80. 85

As above noted, the movement of the rock shaft 62 from the shaft 42 at the close of the return movement of the crank not only breaks the clutch 37, 38 to disconnect the carriage from the motor, but also breaks the 90 motor circuit by rocking the bell crank 112 clockwise, permitting the spring 120 to throw up the switch piece 115, breaking the connection to the contact 119 at 118. The motor is thus silenced. While the shaft 62 100 is effecting this operation, it is also forcing the rod 58 forwardly, until finally the shoulder 65 on the latter, drops in front of the shoulder on the holding piece 66. The parts are now all in position ready for the letter- 105 feed movement of the carriage.

In order that the motor may be connected to the carriage to return it to the beginning of a line from any intermediate point thereof, there is provided (see Fig. 1) a key 140 110 having a connection 141, working in a slot 142, to a bell crank lever 143 pivoted to the frame at 144. The vertical arm 145 of this lever has a cam surface 146 at its upper end to engage a dog 147 pivoted at 148 to the 115 end of the slide bar 58. A stop 149 on the slide bar causes the dog 147 to rise as a unit with the slide bar when the key 140 is depressed, thereby lifting the shoulder 65 on the slide bar out of contact with the holding 120 piece 66, and releasing the bar to the action of the spring 64, whereby, through the mechanism heretofore described, the connections from the motor to the carriage are established, and the motor circuit established 125 through the contacts 117 and 119. A coil spring 153 (see Fig. 1) serves to hold the key 140 in normal position and to return it to the normal position when released, and a stop 154 determines the normal position of 130

the key and its connected lever. The stop 149 on the slide bar 58, while causing the latter to move as a unit with the bar when the key is depressed, does not prevent the 5 dog 147 from having a movement permitting it to clear the key lever 145 when the bar 58 is returned to normal position, as hereinbefore described when the carriage has reached the beginning of the line. It is to be noted that 10 the key lever 143 has no connections to any of the other mechanism, and that all movements resulting from operation of the key lever 143 are effected by the motor, except the movement of the slide bar 58 which is 15 effected by the spring 64. This structure renders unnecessary any continued depression of the key 140, and also makes the operation of the latter extremely light.

It is often desirable that after the carriage reaches the end of its normal travel, a margin button be used so that a star may be printed and a word printed after the star, or that something further be written before the parts are delivered to the return action 25 of the motor. Obviously, if, at the end of normal travel of the carriage, the roller 47 were invariably to release the slide bar 58 to the action of the spring 64, this purpose could not be accomplished. In order, therefore, to delay or suspend as long as may be 30 desirable, the action of the slide bar 58, the following attachment to the margin button is provided.

Referring to Figs. 2, 3, 4, 6 and 7, the 35 margin button is shown at 155 having a coil spring 156 for holding it in and returning it to normal position. Opposite and adjacent to the end 155^a of the button 155, is a two-armed lever 157 pivoted to the frame at 158, 40 the upper arm of which lever is turned to present a cam surface 159 to the button, by means of which the lever 157 is rocked about its pivot when the button plunger is depressed. In the normal position of the slide 45 bar 58, that is to say, in the position shown in Fig. 2, in which the shoulder 65 is engaged by the holding member 66, a slot 160 lies opposite the end of the lower arm 161 of the lever 157, in such a position that the 50 movement of the lever 157 by depression of the button causes the lever arm 161 to enter the groove 160 as shown in Figs. 3 and 7. If, at this time, the roller 47, by engagement 55 with the cam 50, causes the slide bar 58 to be lifted, to release the shoulder 65 from the retaining piece 66, the slide bar 58 will nevertheless be prevented from responding to the action of the spring 64 by reason of the position of the lever 157 in the slot 160. 60 Consequently, even though the carriage has reached the end of its normal or prearranged travel, by holding the button 155 depressed, a star and a word, or other writing, may be made before the motor connections are established. As soon, however, as the pressure is

removed from the margin button and the latter is released to its spring 156, a leaf spring 162 throws the lever 157 against its stop 163, and out of engagement with the slide bar 58; thereby releasing the latter to 70 the spring 64, and putting into action all the operations which were abnormally held in abeyance by the margin button.

The general operator indicated at 107, when actuated, throws forwardly the rack 75 bars 165 which rotate the dials of the accumulator 166. The extent of movement of the rack bars is determined by the particular one of the pins 167 thereon, which has been set from the corresponding numeral key 2. 80 The pins 167 are directly set from linkages 168, when the particular rack bar upon which a pin has been set has been itself set or lifted, so as to be brought within reach of the linkages 168. The linkages are operated from the numeral keys by means of thrust links 169, which, when the keys are depressed, engage arms 170 on rock shafts 171, to each of which shafts one of the linkages is connected by an arm 172, so that 90 upon depression of any numeral key, a rock shaft is turned and a linkage depressed to strike the pin 167 in register therewith on the pin bar 165, which itself has been set. The setting of the pin bars 165 is effected 95 from selector dogs 173 on the carriage. Each selector dog is provided with a tappet 174, which, during the travel of the carriage, comes successively into engagement with the individuals of a series of jacks 175. These 100 jacks depress thrust links 176, and through levers 177, and transposition mechanism 178, raise the rack or pin bars 165 into co-operative relation with the linkages 168. The specific form of computing mechanism does 105 not in itself form a part of the present invention, and need not be set forth further in detail.

The typewriting machine frame 179 may be removably supported on the casing 180, 110 and the latter in turn removably connected to the framework 181 which supports the motor and transmission gearing. To permit the removal of the typewriting machine, the lower ends of the electrical contact bars 115 17 and 119 are bent forward as shown in Fig. 1 and rest on contact bars 182 and 183 in the casing 180, the bars 182 and 183, in turn bearing upon conductors 184 and 185 (see Fig. 9). The conductors 184 and 120 185 are respectively connected to binding posts 186 and 187, extending into a junction box 188. Electrical current from any suitable source such as indicated at 189 (see Fig. 8) is supplied through the main cable 125 190, comprising a conductor 191 connected with the binding post 187, and a conductor 192 to an intermediate binding post 193. A cable 194 extending from the junction box 188 comprises conductors 195 and 196, con- 130

nected to the binding posts 193 and 186 respectively. These conductors 195 and 196 may be connected to the motor terminals. A conductor 197 branching from the conductor 196 leads to one terminal 150 of the transmission clutch switch (see Fig. 5), and a conductor 198 leads from the binding post 187 to the other terminal 151 of that switch. The circuit through the transmission clutch switch is therefore from the source 189, by way of conductor 192, binding post 193, conductor 195, motor, conductors 196, 197, switch terminals 150, 151, conductor 198, binding post 187, and conductor 191 to the source 189. The circuit through the switch for maintaining the carriage drive is from the source 189 by way of conductor 192, binding post 193, conductor 195, motor, conductor 196, binding post 186, conductor 184, switch contacts 117, 115, 119, conductors 183, 185, binding post 187, and conductor 191 to the source 189.

Variations may be resorted to within the scope of the invention, and portions of the improvements may be used without others.

Having thus described my invention, I claim:

1. In a combined typewriting and computing machine, the combination with typewriting mechanism including a carriage, and computing mechanism, of actuating means for said computing mechanism, means controlled by the carriage for setting into operation said actuating means, means also controlled by said carriage to return the carriage to begin a new line, means for printing, and means adapted to be manually made effective for holding in abeyance the return of the carriage, pending printing after said carriage has controlled the actuation of said computing mechanism.

2. In a combined typewriting and computing machine, the combination with a traveling carriage and a motor, of computing mechanism in which numbers are adapted to be set up, a device settable to cause the motor to be effective to operate said computing mechanism to compute the numbers set up, a separately-settable device adapted to be set to automatically cause the motor to return the carriage, a rod through which said last device is effective, a spring normally tending to make said rod effective, a catch normally holding said rod, but adapted to be made ineffective by said last-named device to cause the motor to return the carriage, a key operable to make said rod effective at will, and a finger-piece adapted to temporarily restrain said rod, but adapted, upon its release, to permit the spring to make the rod effective.

3. In a combined typewriting and computing machine, the combination with a traveling carriage and a normally idle motor, of computing mechanism in which num-

bers are adapted to be set up, a device settable to cause the motor to start and to be effective to operate said computing mechanism to compute the numbers set up, a separately-settable device adapted to be set to automatically cause the motor to start and to return the carriage, a rod through which said last device is effective, a spring normally tending to make said rod effective, a catch normally holding said rod but adapted to be made ineffective by said last-named device to cause the motor to return the carriage, a key operable to make said rod effective at will, and a finger-piece adapted to temporarily restrain said rod, but adapted, upon its release, to permit the spring to make the rod effective.

4. In a combined typewriting and computing machine, the combination with a traveling carriage and a motor for returning the carriage, of computing mechanism on which a number is adapted to be set up, connections whereby the motor may operate the computing mechanism to compute the number so set up, a tappet settable to cause the automatic operation of the computing mechanism by the motor, at a time determined by the travel of the carriage, a separately-settable device to cause the carriage to be automatically returned by said motor, and a finger-piece adapted to be operated to inhibit the operation of said device.

5. In a combined typewriting and computing machine, the combination with a traveling carriage and a normally idle motor for returning the carriage, of computing mechanism on which a number is adapted to be set up, connections whereby the motor may operate the computing mechanism to compute the number so set up, a tappet settable to start the motor and cause the automatic operation of the computing mechanism thereby, at a time determined by the travel of the carriage, a separately-settable device to start the motor and cause the carriage to be automatically returned thereby, and a finger-piece adapted to be operated to inhibit the operation of said device, but adapted on its release to start the motor and cause the return of the carriage.

6. In a combined typewriting and computing machine, the combination with a traveling carriage and computing mechanism, in which numbers are adapted to be set up, of power connections for causing the set-up numbers to be computed, power connections for returning said carriage, a tappet settable to cause the travel of the carriage to automatically make said first-named connections effective to compute, a device adapted to be set to be effective at the same time to cause said second-named connections to be effective to return the carriage, and a finger-piece adapted to be operated to hold said last-named connections ineffective,

said last-named connections adapted to be made effective at the release of said finger-piece.

7. In a combined typewriting and computing machine, the combination with a traveling carriage and a motor, of computing mechanism in which numbers are adapted to be set up, a device settable to cause the motor to be effective to operate said computing mechanism to compute the numbers set up, a separately-settable device adapted to be set to automatically cause the motor to return the carriage, a rod through which said last device is effective, a spring normally tending to make said rod effective, a catch normally holding said rod but adapted to be made ineffective by said last-named device to cause the motor to return the carriage, and a finger-piece adapted to temporarily restrain said rod, but adapted, upon its release, to permit the spring to make the rod effective.

8. In a combined typewriting and computing machine, the combination with a traveling carriage and a normally idle motor, of computing mechanism in which numbers are adapted to be set up, a device settable to cause the motor to start and to be effective to operate said computing mechanism to compute the numbers set up, a separately-settable device adapted to be set to automatically cause the motor to start and to return the carriage, a rod through which said last device is effective, a spring normally tending to make said rod effective, a catch normally holding said rod but adapted to be made ineffective by said last-named device to cause the motor to return the carriage, and a finger-piece adapted to temporarily restrain said rod, but adapted, upon its release, to permit the spring to make the rod effective.

9. In a combined typewriting and computing machine, the combination with a traveling carriage and a motor for returning the carriage, of computing mechanism on which a number is adapted to be set up, connections whereby the motor may operate the computing mechanism to compute the number so set up, a tappet settable to cause the automatic operation of the computing mechanism by the motor, at a time determined by the travel of the carriage, a sepa-

rately-settable device to cause the carriage to be automatically returned by said motor, a key ineffective on the computing mechanism, but adapted to be depressed to cause the motor to return the carriage, and a finger-piece adapted to be operated to inhibit the operation of said device.

10. In a combined typewriting and computing machine, the combination with a traveling carriage and a normally idle motor for returning the carriage, of computing mechanism on which a number is adapted to be set up, connections whereby the motor may operate the computing mechanism to compute the number so set up, a tappet settable to start the motor and cause the automatic operation of the computing mechanism thereby, at a time determined by the travel of the carriage, a separately-settable device to start the motor and cause the carriage to be automatically returned thereby, a key ineffective on the computing mechanism, but adapted to start the motor and cause it to return the carriage, and a finger-piece adapted to be operated to inhibit the operation of said device, but adapted on its release to start the motor and cause the return of the carriage.

11. In a combined typewriting and computing machine, the combination with a traveling carriage and computing mechanism in which numbers are adapted to be set up, of power connections for causing the set-up numbers to be computed, power connections for returning said carriage, a tappet settable to cause the travel of the carriage to automatically make said first-named connections effective to compute, a device adapted to be set to be effective at the same time to cause said second-named connections to be effective to return the carriage, a key operable to make said second-named power connections effective to return the carriage, but ineffective on the computing mechanism, and a finger-piece adapted to be operated to hold said second-named connections ineffective, said second-named connections adapted to be made effective at the release of said finger-piece.
